Specification for Design.

Patented Apr. 18, 1916.

Application filed January 15, 1916. Serial No. 72,364. Term of patent 7 years.

To all whom it may concern:

Be it known that I, CHARLES A. LAPWORTH, a citizen of the United States, residing at West Bridgewater, in the county of Plymouth and State of Massachusetts, have invented a new, original, and ornamental Design for Elastic Fabrics, of which the following is a specification, reference being had to the accompanying drawing, forming part thereof.

The figure is a plan view of a portion of a fabric showing my design.

Copies of this patent may be obtained for five cents each, by addressing the "Commissioner of Patents, Washington, D. C."

I claim—

The ornamental design for an elastic fabric substantially as shown.

In testimony whereof, I have hereunto subscribed my name.

CHARLES A. LAPWORTH.
